UNITED STATES PATENT OFFICE.

FRED TOEPFER, OF VICTORIA, KANSAS.

UNLOADING DEVICE FOR HEADER-BOXES.

1,373,987.

Specification of Letters Patent.

Patented Apr. 5, 1921.

Application filed April 2, 1919. Serial No. 286,891.

To all whom it may concern:

Be it known that I, FRED TOEPFER, a citizen of the United States, residing at Victoria, in the county of Ellis and State of 5 Kansas, have invented certain new and useful Improvements in Unloading Devices for Header-Boxes, of which the following is a specification.

This invention relates to an improved unloading device for a header-box and the principal object of the invention is to provide a structure of the character described which will constitute a false bottom for the header-box and may be moved vertically to 15 a dumping position, the false bottom being connected with the draft gear through the medium of cables and the cables being further so arranged that as the false bottom moves upwardly it will be raised to a tilted 20 position thus permitting the material resting upon this false bottom to pass out at one side of the wagon body.

Another object of the invention is to so construct this device that the tilting will 25 increase as the false bottom moves upwardly to the elevated position and the false bottom then returned to a horizontal position as it moves downwardly after dumping the load.

Another object of the invention is to so 30 construct this device that the cables may be independently locked against movement thereby permitting the angle of the false bottom when in a raised position to be changed.

35 Another object of this invention is to so construct the elevating mechanism for the false bottom that the draft-animals used for drawing the header-box across a field may be used for raising the false bottom.

40 Another object of the invention is to so construct this device that it will be simple in construction and not liable to easily get out of order.

This invention is illustrated in the accompanying drawings wherein:

Figure 1 is a view showing a header-box in side elevation and provided with the improved unloading structure.

Fig. 2 is a top plan view of the improved 50 header-box and unloading structure.

Fig. 3 is a view showing the improved headerbox in end elevation,

Fig. 4 is a transverse sectional view 55 through the improved headerbox and unloading structure, and

Fig. 5 is an enlarged fragmentary sectional view showing the clutch for engaging one of the cables.

This header-box is provided with a body or receptacle indicated in general by the 60 numeral 1 and having one side wall 2 of greater height than the other, said wall 2 having an upper section 3 hingedly mounted so that it may be swung down as indicated in Fig. 3 when unloading the header-box. 65 At each end of this header-box there will be provided a standard or supporting arm 4 which extends above the header-box at a point intermediate its width and will be braced by the bracing bars 5 and 6 leading 70 from the upper and lower ends of the vertical bar 7. Beneath the header-box there will be provided forward and rear supporting frames 8 and 9 which carry pulleys 10 and 11 the purpose of which will be herein- 75 after brought out. Pulleys 12 are carried by the standards 4 and pulleys 13 are carried by the upper end portions of the vertical arms 7 and coöperate with the pulleys 10 and 11.

A false bottom 14 fits into this header-box and is provided with end bars 15 having slots 16 formed adjacent one side of the header-box and provided at their opposite ends with rollers 17 to engage the side wall 85 2 and thus provide means for permitting the false bottom to move easily in the header-box. Cables 17^a, 18, 19 and 20 are connected with this false bottom 14, the cables 17^a and 19 being connected with the pulleys 21 90 and being passed around the pulleys 12 and back to the pulleys 21 around the wheel thereof and being then carried over the pulleys 12. The cable 17 will be led to engage one of the forward pulleys 10 and the sec- 95 ond cable 19 will be led to engage one of the pulleys 11 and will then be carried forwardly beneath the bottom of the header-box. It should be noted that the pulleys 21 have extended end portions providing necks 100 which pass through the slots 16 and carry side rollers 22 which engage the false bottom and permit the pulleys to move easily in the slots 16. The cables 18 and 20 will be connected with the pulleys 13 and will 105 then be carried about the pulleys 23 connected with the false bottom and after being passed back through the pulleys 13 will again be brought into engagement with the pulleys 23 and will be carried over the pul- 110

leys 13 and led down beneath the bottom of the header-box. The forward cable 18 will engage the remaining pulley 10 and the cable 20 will engage the second pulley 11 and 5 be then carried forwardly toward the forward end of the header-box. These cables are carried forwardly beyond the forward end of the header-box through a housing 24 and pass between the locking levers 25 10 and clamping block 26 and have their free ends connected with the double-tree 27 of the draft gear. These cables will be releasably connected with the double-tree so that when desired certain of the cables may 15 be released from the double-tree. This double-tree will be of a conventional construction and may be connected with the usual tongue of the vehicle when the header-box is being drawn across a field.

20 In the operation of this improved header-box unloading device the draft-animals will be connected with the draft gear and the header-box can then be drawn across a field and loaded. While the header-box is being 25 loaded the false bottom will remain in the bottom of the header-box and will not be moved as the header-box is drawn across a field due to the fact that the double-trees will be connected with the tongue of the vehicle. After the header-box has been loaded 30 and it is desired to empty the same the vehicle will be brought to a stop at the point where it is desired to unload and the double-tree will then be released from the tongue. 35 The draft-animals will then be driven forwardly and as they move forwardly will pull upon the cables thus causing the false bottom to be drawn upwardly. As the pulleys 23 and 13 are double pulleys and the 40 pulleys 21 and 12 are single and double respectively, movement of the draft-animals forwardly a predetermined amount will cause the side portion of the false bottom engaging the wall 2 to move slower than the 45 opposite side and the false bottom will therefore be positioned at an incline and will slope toward the wall 2. Therefore when the false bottom is in the raised position the load can be easily passed out of the header- 50 box over the lowered upper section 3 of this wall 2. If the incline of the false bottom should not for any reason be proper the cables 18 and 20 can be released from the double tree and engaged by their respective 55 clamping lever. The draft-animals can then be moved forwardly or rearwardly until the false bottom is at the proper incline. It will be further noted that if it is desired to use the draft-animals for any purpose after 60 the false bottom has been raised and while waiting for the header-box to be unloaded the cables may all be engaged by their clamps and the horses then disconnected. It will be further noted that due to this construction the false bottom may be retained 65

in a raised position by clamping these cables and thus strain removed from the horses. After the header-box has been unloaded the draft-animals will be backed into position and as they move rearwardly into position 70 the false bottom will be lowered and will assume a horizontal position.

What is claimed is:

1. The combination with a header-box 75 having sides; of standards connected with the header-box and extending above the same, a false bottom positioned in the header-box to ride upwardly upon one of the sides, pulleys connected with the standards, a draft appliance, and cables leading from 80 the draft appliance and over the pulleys of the standards and connected with the false bottom for lifting said bottom to an elevated and tilted position.

2. The combination with a header-box 85 having sides; of a false bottom loosely positioned in the header-box to ride upwardly upon one of the sides, standards connected with the header-box and extending above the same, a draft appliance, pulleys connected with the standard, single and double pulleys connected with the false bottom for unevenly lifting the same, certain of the pulleys having sliding engagement with the false bottom, and cables leading from the 90 draft appliance and trained around the pulleys of the standards and false bottom whereby one portion of the false bottom may be vertically moved a greater distance than the other. 95

100 3. The combination with a header-box; of a false bottom mounted to move vertically therein, a draft appliance, cables connected with the draft appliance and with the false bottom whereby said bottom may be vertically adjusted through the medium of the cables, and dogs engaging the cables to releasably hold them and retain the false bottom in a vertically adjusted position.

105 4. The combination with a header-box; of a false bottom positioned in said box for vertical movement, a draft appliance, means connecting the draft appliance with one side of the false bottom for vertically adjusting said bottom as the draft appliance is moved 110 away from or toward the header box, means connecting the draft appliance with the other side of the false bottom for imparting vertical movement to said bottom as the draft appliance is moved at a different rate 115 of speed to the movement to the first mentioned side of the false bottom thereby causing said bottom to move from a substantially horizontal position to an inclined position as it moves upwardly and returns to the horizontal position as it moves downwardly. 120

125 5. The combination with a header-box having side walls and a releasable section carried by one side wall; of a false bottom in the header-box movable vertically therein 130

with one edge thereof engaging one of the sides beneath the releasable section, a draft appliance, and means connecting the draft appliance with the false bottom for imparting vertical movement to the false bottom, with the side portion of the false bottom remote from the wall equipped with the re-

leasable section traveling at a faster rate of speed from the side portion of the false bottom adjacent the wall equipped with the releasable section.

In testimony whereof, I affix my signature hereto.

FRED TOEPFER.
